UNITED STATES PATENT OFFICE

MATTHEW M. FRIEDEMANN, OF NEW YORK, N. Y.

SHOW CARD HOLDER FOR DISPLAY STANDS

Application filed June 12, 1928. Serial No. 284,861.

This invention relates to display devices, particularly to a show card holder for display stands or similar devices. It is an object of my invention to provide a display device, particularly of the knock-down type, whose display area and number of display elements may be varied and associate therewith a show card holder which may equally be varied as to its size to permit association with the display assembly of a show card which will be attractive in appearance and combine with various sizes of the display assembly to obtain maximum ornamental effects. It is contemplated by my invention to provide a show card holder for display stands which may be varied to accommodate cards of varying sizes and retain the same in an attractive frame to be associated with the display assembly, it being further contemplated by my invention that a show card may be made and framed without giving any unusual care to the size of the show card and still provide a framing member therefor.

It is a still further object of my invention to provide a frame member to be assembled with a display assembly and which may be accommodated and varied to take on and frame a large number of forms and sizes of cards. It is a still further object of my invention to provide a show card holder for display stands or assemblies, particularly of the type using telescopic posts or standards, which are built up in various sizes and including a varying number of shelves whereby the show card holder may be interchangeable with any one of a number of display stands and varied in accordance with the varying proportions of the standard to hold and display a show card of varying dimensions. Other objects of my invention reside in the provision of a frame member or show card holder which may be varied in size, which is simple and inexpensive to manufacture, and has a high degree of utility in dressing and arranging display devices.

To attain these objects and such further objects as appear herein or may be herein-after pointed out, I make reference to the

accompanying drawings forming a part hereof, in which—

Figure 1 is a perspective view of a fragmentary portion of a display assembly illustrating my invention;

Figure 2 is a side elevation of an enlargement, parts being broken away to show the details;

Figure 3 is a section taken on a line 3—3 of Figure 2;

Figure 4 is a section taken on a line 4—4 of Figure 2;

Figure 5 is a section taken on a line 5—5 of Figure 1;

Figure 6 is a fragmentary plan view of another embodiment of my invention.

Making reference to the drawings my invention has particular utility with a display assembly comprising a standard 10 which is preferably a square tubular member which serves to support any number and size of display shelves 11, which are affixed to the standard by the brackets 12, engaging the apertures 13. This bracket or display shelf holder may be of the character disclosed in the patent to Slifkin 1,554,187, dated September 15, 1925. For finishing off the upper portion of the standard 10 I may provide an ornamental plug 14 and it is preferred to associate with this ornamental plug a show card holder. The ornamental plug comprises a block 15 whose cross sectional contour corresponds to the square tubular member and is provided with the bracket clearance slots 16, so as not to interfere with the attaching members of the display shelf, as will be readily understood. Centrally through the plug 15 I provide an aperture 17 through which I attach the securing bolt 18, which is threaded at the end 19 to take the nut 20. Next mounted upon the block I may position a spacer block 21, over which there is fitted the ornamental plug 14, the same being held in fixed position by the show card frame nut 22 engaging the threaded end 23 of the bolt 18. The show card frame comprises a channel member 24 which is adapted to be received in the bifurcated portion 25 of the show card frame nut 22, previously mentioned. I may

100

position the channel member 24 frictionally within the bifurcated portion 25 or fixedly attach the same by spot welding or soldering. Disposed to each end of the channel member 24 I provide channel angle members 26, one arm of which 27 is formed of a cross section adapted to envelop the channel member 24 and this comprises the side arms 28 having inwardly directed lips 29, 10 engaging the upper edges of the channel member. It will be observed that by the construction shown the arm 27 has telescopic, sliding engagement with the channel 24, thereby permitting relative adjustment of 15 the channel 24 and the angle channel 26 relatively to each other. In order to fix the position, for purposes which will appear hereafter, it is preferred that the bottom wall of the arm 27 have a longitudinal orifice 30, through which there is passed a fastening element 31, preferably making screw engagement with the bottom wall of the channel 24 at 32. This fastening element 31 is preferably a headed screw. It will be 20 observed that this headed screw may be utilized to fix the arm 27 at any predetermined position along the channel 24 within the limits of the slot 30, previously mentioned.

25 The second arm 33 of the angle 26 may be formed of the same contour as the arm 27, as previously described. It is preferred, however, for one embodiment of my invention, to dispose within the channel of this arm a vertical channel 34, rigidly affixed thereto. The side walls 35 of this channel are preferably spring arms and include camming lips 36.

30 It will be observed that for forming a show card frame I duplicate the arms 27 to each side of the channel member 24 so as to obtain a symmetrical arrangement of the angles and the channel 34 carried thereby. By this arrangement I may provide a narrow or wide frame comprising relatively 35 slideable telescopic channel members and dispose within the channel members a show card 37 of any desired size, the same being rigidly held by the spring side walls 35 of the channel 34. The device so provided may 40 be associated in connection with any display device for mounting a show card in connection therewith in a neat and ornamental manner, convenience of the device being obtained by reason of requiring no special 45 measurement of the show card to be associated with the display device, the frame therefor being capable of accommodation through a wide range of sizes. It is preferred that this device be used in connection 50 with the display assembly disclosed in my application S. N. 281,408, filed May 29, 1928, wherein a hollow, tubular standard may be ornamentally finished off at the top thereof 55 by insertion of the ornamental plug 14 with

or without its fitting comprising the show card holder frame. With a variable display assembly, the show card frame may be varied, and enlarged or diminished in proportion to the display device.

70

In Figure 6 I have fragmentarily shown another embodiment wherein the frame may be completely formed on all four sides and enlarged or diminished in two dimensions. For this purpose the channel angle members 75 26 are formed with both arms 27 and 33 of the same cross sectional contour and the vertical arms 34 replaced by a channel member such as 24.

In Figure 6 I have shown an extreme left 80 hand corner of a member which forms part of a completely enclosed frame in which the angle channel member 26' has the arms 27' of the same construction as the arm 27 of the embodiment illustrated in Figures 1 to 4 85 and is provided with the side arms and inwardly turned lips 29'. A longitudinal orifice 30', equivalent to that shown at 30 in Figure 2, is also provided. This angle channel member thus provided is adapted to receive horizontal and vertical channel members 24' and 34', equivalent to channel member 24. Through the slots 30' there is passed the fastening element 31' engaging a screw threaded orifice 32' as in the manner 90 described in connection with the arm 27. It will be understood that all four corners of the completed frame are provided with similar, symmetrically disposed angle channel members.

95

100 By this construction I may form a completed frame with slideable, telescopically engaging horizontal and vertical members whereby the frame may be enlarged or narrowed at will in two dimensions to completely frame a show card and, furthermore, provide simple means for inserting a show card within the frame without modification of the frame but merely by extending it to permit insertion.

105

110 In general, it will be observed that I have provided a show card holder for display standards which may be varied at will to accommodate the same to various sizes of show cards, at the same time accommodating the 115 size of the frame to any variation in the display assembly.

115

Having thus described my invention and illustrated its use, what I claim as new and desire to secure by Letters Patent, is—

120

125 In a display assembly including a tubular standard, a show card holder or frame including a plug member, one end thereof including a portion including a fitting to be disposed in coupling engagement with said standard, the opposite end of said member comprising a bifurcated extension, an open sided channel fitted within said bifurcated section, channel angle members comprising side branches disposed to either side of said 130

open sided channel including inwardly directed lips engaging the upper edges of said member and enveloping the same loosely for sliding engagement therewith, slots formed in said angle members, fastening members disposed through said slots engaging said channel whereby said angle members may be disposed at predetermined positions and extend the side branches relatively to each other.

10 In witness whereof I have hereunto signed my name this 8th day of June, 1928.

MATTHEW M. FRIEDEMANN.
